SHEET MUSIC TURNER

Albert Maletta, Yakima, Wash.

Application September 26, 1944, Serial No. 555,852

6 Claims. (Cl. 84—503)

My invention relates to the disposition of sheet music and the like, and has among its objects and advantages the provision of an improved sheet music turner.

In the accompanying drawings:

Figure 1 is a front elevational view of a conventional music stand illustrating my invention applied thereto;

Figure 2 is a side elevational view;

Figure 3 is a detail view of a turning mechanism enclosed in a cabinet constituting a base, with one wall of the cabinet removed;

Figure 4 is a sectional view along the line 4—4 of Figure 3;

Figure 5 is a fragmentary detail view of the sheet turning gripper mechanism;

Figure 6 is a sectional view along the line 6—6 of Figure 5;

Figure 7 is a sectional view along the line 7—7 of Figure 5;

Figure 8 is a sectional view along the line 8—8 of Figure 5;

Figure 9 is a view taken from the position indicated by line 9—9 of Figure 8;

Figure 10 is a sectional detail view of a swivel joint;

Figure 11 is a sectional view along the line 11—11 of Figure 10;

Figure 12 is a sectional detail view of a portion of the swivel joint;

Figure 13 is a perspective view of a sheet music bar attached to the rack 12 for supporting the sheet music at the proper height; and

Figure 14 is a sectional view of one of the claims which connect my invention with the sheet music stand for support.

In the embodiment selected for illustration, Figures 1 and 2 illustrate a conventional music stand 10 having the usual rack 12 connected with a rod 14 telescopically connected with a sleeve 16 to which the supporting legs 18 are connected.

My invention comprises an upright tube 20 bolted at 22 to a mechanism-enclosing cabinet and base 24, which rests on the floor 26 with the legs 18. A removable cover 28 is provided for the cabinet 24.

Inside the cabinet 24 and to one wall thereof is bolted a plate 30, as at 32, to which plate is pivoted a T bar 34, as at 36. To each of the branches 38 of the T bar 34 is pivotally connected at 40 one end of a link 42. Each link 42 is engaged by a spring 44 which urges that link against the other. Both springs 44 are secured to a tubular guide member 46 mounted

on the plate 30. A slide bar 48 is slidably guided in the tubular member 46 and has its upper end arranged for selective engagement with shoulders 50 on the links 42.

5 To the lower end of the slide bar 48 is connected one end of a tension spring 52, the other end of the spring being connected with a pin 54 attached to the cabinet 24. The spring 52 normally holds the bar 48 in the position of Figure 3, further downward movement of the bar being restrained by reason of a pin 56 attached thereto for engagement with the upper end of the tubular member 46. Foot operated lever 58 extends through an opening 60 in one wall of the cabinet 24, and the lever is pivoted intermediate its ends to the cabinet, as at 62. A link 64 connects the inner end of the lever 58 with the lower end of the slide bar 48 so that downward movement of the exterior end of the lever 58 imposes upward movement to the slide bar 48.

When viewed according to Figure 3, upward movement of the slide bar 48 imparts corresponding movement to the link 42 engaged by the bar. Such upward movement of this link 42 imparts counter-clockwise rotation to the T bar 34. Upon completion of its counter-clockwise movement, the T bar 34 imparts downward movement to the left hand link 42 to bring its shoulder to a position corresponding to the shoulder on the right hand link in Figure 3. When the lever 58 returns to its normal position of Figure 3, upward movement of the slide bar 48 will engage the shoulder 50 of the left hand link 42 for pivoting the T bar 34 in a clockwise direction to the position of Figure 3. Guide bars 66 engage opposite sides of the T bar 34 to provide a supporting track for the bar as it is pivoted from one position to the other.

40 A right angular bend 68 is formed at the upper end of the T bar 34, to which bend is connected a U-shaped member 70 through the medium of a swivel joint 72. A strap 74 extends loosely between the opposed side elements of the U-shaped member 70 and is fixedly connected with an upper shaft 76 rotatably journaled in a bearing 78 attached to the cabinet 24 and in a bearing 80 located inside the tube 20 near its upper end, see Figure 10. Thus oscillatory movement of the T bar 34 is translated into rotary motion of the shaft 76.

45 Referring to Figures 10 and 12, a universal joint 82 connects the upper end of the tube 20 with a head 84. This universal joint comprises a socket member 86 having its neck 88 fixedly secured to the tube 20 by screws 90. A ball mem-

ber 92 fits inside the socket member 86 and is provided with a flange 94 fixedly secured to the head 84 by screws 96, see Figure 10.

In Figure 7, the head 84 is of hollow formation and is provided with an opening 98 for the passage of a flexible shaft portion 100 having one end connected with the shaft 76 and its other end connected with a shaft 102 mounted in a bearing 104. To the shaft 102 is fixedly secured a gear 106 by a set screw 108. The gear 106 lies on an internal flange 110 in the head 84 and meshes with a pinion 112 mounted on a shaft 114 having one end disposed in an opening in a flange 116 on the head 82 and its other end lying in an opening in a cover 118 secured to the flange 116 by screws 120.

To the pinion 112 is fixedly secured an arm 122 upon which is slidably mounted two sheet grippers 124. Each sheet gripper 124 comprises a resilient and transparent strap 126 and a resilient and transparent strap 128. The strap 126 has a body 130 connected with a slide 132 sliding on the arm 122, while the strap 128 has its lower end pivotally connected with the body 130 by a screw 134. A spring 136 has one end engaging the strap 128 and its other end engaging the body 130 for yieldingly holding the strap 128 vertically in opposing engagement with its companion strap 126. A rounded corner 138 is provided on the strap 128 so that this strap may be pivoted in one direction downwardly in the direction of the arm 122.

To firmly secure the tube 20 to the stand 10, brackets 140 have loops 142 encircling the tube 20 and spaced resilient elements 144 which snap over the respective bar 14 and the tube 16. Bracket 140 is made in sections 146 and 148 adjustably connected together by a bolt 150 passing through an opening in the section 146 and through a slot 152 in the section 148.

Figures 1 and 2 illustrate the head 84 in its operating position with respect to the rack 12, the universal joint 82 permitting precise adjustment of the head with respect to the rack. The socket member 86 comprises sections 154, see Figure 11, having flanges 156 which are connected by a screw 158 and a hand screw 160. Tightening of the screw 160 clamps the socket 86 to the head 92 so as to prevent accidental pivotal movement thereof.

A bar 162 is provided with clips 164 for connection with the rack 12 to support the supply 166 of sheet music.

With a sheet of music 168 gripped between the straps 126 and 128 of the respective grippers 124, the sheet 168 may be turned by applying pressure to the lever 58. Rotation of the shaft 76 imparts rotary motion to the gear 106 which meshes with the pinion 112.

Since the arm 122 is fixedly secured to the pinion 112, rotary motion of the pinion pivots the arm 122 for moving the sheet 168 to the opposite side of the rack 12 and thereby reverses the sheet. In one downward movement of the lever 58, the arm 122 pivots from one position to its second position, and the second downward

movement of the lever 58 pivots the arm 122 from its second position back to its first position.

Without further elaboration, the foregoing will so fully illustrate my invention, that others may, by applying current knowledge, readily adapt the same for use under various conditions of service.

I claim:

1. A sheet music turner comprising a standard 10 having a head, an arm pivoted on said head provided with a sheet gripper means, a foot operated lever, a pivoted T bar movable to first and second positions, a link pivoted to each of two branches of said T bar, means operatively connected with said lever arranged to alternately engage the links to respectively pivot said T bar to said first and second positions, and an operating connection between the third branch of the T bar and said arm to pivot the arm and its gripper means to first and second sheet holding positions upon movement of said T bar to its respective first and second positions.
2. The invention described in claim 1 wherein there is provided a universal joint between said standard and said head, and in which a flexible coupling is interposed in said operating connection at said universal joint.
3. The invention described in claim 1 wherein said operating connection includes a pinion keyed to said arm, a gear meshing with said pinion, a vertical shaft connected with said gear, and an oscillatory arm fixed to said vertical shaft and slidably connected with the third branch of said T bar to oscillate the vertical shaft upon pivotal movement of the T bar.
4. The invention described in claim 1 wherein said links have shoulders selectively engaged by said second-mentioned means, and in which said links are provided with springs biasing the links into engagement one with the other to bring said shoulders into engaging positions with respect to said second-mentioned means in the respective positions of the T bar.
5. The invention described in claim 1 wherein said sheet gripper means each comprises two transparent, resilient straps positioned for pinching a sheet therebetween, one strap in each gripper unit being mounted for pivotal movement with respect to its companion strap, and means slidably connecting each gripper means with said arm.
6. A sheet music turner comprising a standard, an arm pivoted on said standard and provided with a sheet gripper means, a foot operated lever, a pivotally mounted member movable to first and second positions, links pivotally connected with said member, means operatively connected with said lever and arranged to alternately engage the links to respectively pivot said member to said first and second positions, and an operating connection between said member and said arm to pivot the latter and the sheet gripper means to first and second sheet holding positions upon movement of said member to its respective first and second positions.

ALBERT MALETTA.
